DESIGN.

H. DAVIS.

CARPET.

No. 15,317.

Patented Aug. 26, 1884.

UNITED STATES PATENT OFFICE.

HENRY DAVIS, OF PHILADELPHIA, PENNSYLVANIA, ASSIGNOR TO HORNER BROTHERS, OF SAME PLACE.

DESIGN FOR A CARPET.

SPECIFICATION forming part of Design No. 15,317, dated August 26, 1884.

Application filed July 10, 1884. Term of patent 3½ years.

To all whom it may concern:

Be it known that I, HENRY DAVIS, of the city of Philadelphia, and State of Pennsylvania, have invented and produced a new and original Design for Carpets, of which the following is a specification.

The nature of my design is fully represented in the accompanying photographic illustration, to which reference is made.

I claim as my invention—

The design for a carpet, as shown.

Witnesses: HENRY DAVIS.

BENTON O. SEVERN.

STEPHEN SMITH.
